RUDOLF SCHMIDT, OF VIENNA, AUSTRIA, ASSIGNOR TO "PATIAG" PATENTVERWERT-
UNGS- UND INDUSTRIE-AKTIENGESELLSCHAFT, OF VADUZ (LIECHTENSTEIN)

ROTARY PUMP

Application filed February 23, 1928, Serial No. 256,438, and in Austria June 3, 1927.

I have filed applications in Austria 3rd June 1927, Czechoslovakia 10th August 1927, Great Britain 23rd January 1928, Germany 10th October 1927, Switzerland 10th October 5 1927, Hungary 14th January 1928, Yugoslavia 20th January 1928, Rumania 18th January 1928, and of which the following is a specification.

This invention relates to rotary pumps 10 particularly adapted to pumping liquids and of the type wherein a pair of pistons operate in a manner somewhat analogous to the operation of gears with one or two teeth.

In actual practice, rotary pumps of the 15 type to which the present invention relates have heretofore been limited to pumps in which the pistons are provided with alternate, concave and convex portions which are caused to rotate relatively to each other in 20 such a manner that the convex portion of one piston co-operates with the concave portion of the other piston. Examples of such types of rotary pumps are the well known Root's blowers and gear pumps. When the pump 25 pistons are provided with these concave and convex portions, a squeezing of the fluid between such portions of the pump is produced in actual operation with consequent sudden increases and resultant heavy radial stresses 30 on the shafts of the pistons. These objectionable phenomena are greatly magnified with increased rotary speed of the pistons and as a result of these phenomena as well as of the very pronounced lack of uniformity of 35 delivery, the operation of such rotary machines is impossible at the high operating speeds required in modern engineering practice.

In addition to the rotary piston type of 40 pump, there is employed in actual practice rotary pumps of the type known in the art as centrifugal pumps, and while the centrifugal type pump may be operated at high speeds, its use is confined largely to the 45 pumping of gases because of the fact that the centrifugal pump is not capable of producing what may be termed a positive suction. While centrifugal pumps are sometimes employed for the pumping of liquids, 50 it is necessary to provide special priming

means in order to secure a continuous column of liquid in the pump upon the starting thereof. Moreover, centrifugal pumps can not be successfully employed for the pumping of viscous liquids, nor can they be used for 55 high pressures. The principal object of the present invention is to provide a new and improved construction for a rotary pumping machine whereby the objectionable features heretofore present in pumps of this type are 60 obviated and whereby the pump may be used not only at high rotative speeds but where it may be also employed to generate pressures heretofore obtainable only with pumps 65 of the reciprocating type. The essential feature of the pump which forms the subject matter of the present invention resides in the provision of a pair of cam-shaped pistons, the cross-sectional profile of which consists of concentric, circular portions, joined 70 by intermediate curves in such a manner that the entire profile of each cam is free from concave portions and the pair of pistons co-operate with each other without contact. 75

Figure 1 of the accompanying drawings is a diagram representing the invention. Figure 2 is a vertical axial section of a pump with one pair of pistons according to the invention the section being taken on line 80 $x-y$ (Figure 3). Figure 3 is a cross section of the pump shown in Figure 2. Figure 4 represents a vertical axial section through a pump with two pairs of pistons.

In Figure 1 G g denote the double casing of the rotary pump with a cylindrical bore; K is a cam shaped piston of large cross section rotating on axis c in direction of arrow; k a cam shaped piston of considerably 85 smaller cross section, rotating on axis c' in the opposite direction. Each of the two cam shaped pistons K and k together with the corresponding portions of the double casing as well as with a portion of the profile 90 of its cooperating piston, forms an individual, rotary pump with a crescent-shaped working chamber the effective portion of which during each revolution of the piston changes 95 periodically. Both rotary pumps have suc- 100

tion pipe S and delivery pipe D in common.

In order to avoid any interruption of the uniform operation of the pump, both cam shaped pistons must revolve at equal angular velocities and at the same time by continually converging upon each other with an intermediary film of liquid sealing the points of convergence, must shut off suction pipe S from delivery pipe D.

- 10 The cross-sectional profile of each piston, as clearly shown in Fig. 1, consists of a pair or diametrically opposed, concentric, circular portions which are joined by intermediate curves in such a manner that the entire profile of each piston is free from concave portions. In the larger piston K the diametrically opposed, concentric, circular portions are included between the points M, N and M', N', while the intermediate curved portions are included between the points M, M' and N, N', while in the smaller piston k the opposed, circular portions are included between the points m, n, m', n', and the intermediate curves between m, m' and n, n'.
 15 20 25 30 35
- In order to avoid any jamming which might otherwise occur with profiles of this type, the pistons co-operate with one another without actual contact at their points of maximum convergence and with an accurately determined amount of play just sufficient to avoid actual contact but to permit the presence of the intermediary sealing film of liquid above referred to.

The construction of the pistons is such that when each piston is in its zero position, i. e., with its larger radius, circular portion adjacent to the suction and delivery ports, and with the piston in a position such that it is symmetrically disposed with respect to a plane passing through the axes of the pistons, it must cut off its own working chamber from the delivery and intake pipe. This requirement is fulfilled by an ample dimensioning of the angle α corresponding to the concentric, circular portions M, N and m, n, respectively. It will be seen by referring to Fig. 1 which shows the smaller piston k in its zero position, that the concentric portion m, n thereof extends from the edge of the suction port S to the edge of the delivery port D. When the larger piston K is in its zero position (that is rotated through 180° from the position shown in Fig. 1) its circular portion M', N' of its profile of large radius will extend from the lower edge of the suction port S to the lower edge of the delivery port D, thereby sealing or cutting off communication between the suction and delivery sides of the lower working chamber.

In order that the rotary pump may be capable of being rotated at high speeds it is of the greatest importance that uniform delivery during each rotation of the pump be approximated as closely as possible, or at

least that sudden or marked variations in the pressure conditions be avoided.

These conditions are fulfilled if

$$R + r = \frac{l}{cc'} = \text{constant if the thickness of the fluid film between the curved parts is neglected where } R \text{ or } r \text{ denote the variable radii of both cam shaped pistons respectively and } l \\ 70 \\ 75$$

cc' denotes the invariable distance between the axes of rotation of the two pistons.

If a certain contour line be adopted for one of the two pistons the contour line for the second piston will be determined as a fixed shape by applying the aforementioned formula. The formula gives the same law and correspondingly the same contour lines for the pump output of both pistons during one complete revolution, which will become evident from the following consideration:—

If piston K be turned in the direction of arrow (Figure 1) through angle φ , the radius of contact is increased by an amount a resulting in a corresponding decrease of the amount of liquid drawn-in or delivered respectively at this moment. The radius of contact for the governing piston k must, however, be decreased by the same amount a , resulting in a corresponding increase of the amount of liquid drawn-in or delivered respectively by this piston, if the equation

$$R + r = \frac{l}{cc'} \text{ is to be fulfilled in the new relative position of both pistons. Moreover from this it follows that, if piston K be shaped in such a manner as to cover suction- and delivery-passages when in zero position, piston k will do likewise in its analogous position.} \\ 100 \\ 105$$

According to Figures 2 and 3, the two pistons show the same dimensions. 1 denotes the casing common to both pistons 2 and 3, 4 is the suction branch and 5 the delivery branch. Piston 2 is mounted on a driving shaft 6, which runs in ball-bearings 7 and 8. 9 is a pinion keyed on to a shaft 6, gearing with a pinion 10 of the same diameter and with the same number of teeth, which itself is keyed onto the shaft 11 with piston 3. 12 and 13 are ball-bearings for shaft 11.

In order to ensure a more effective lateral packing, the casing may, if desired, be provided with liners 14 and 15 arranged between pistons 2 and 3 and the side walls of the casing, butting against the end walls of the casing by means of packing rings 16. The spaces 20, enclosed by the side walls of casing and liners, on both sides, are connected with the delivery side of the rotary pump by ducts 21 (Figure 2) with the resulting effect that the liners are continually pressed against the cheeks of both pistons, automatically adjusting themselves under the pressure of the liquid by moving inwards should they themselves or the pistons experience any wear.

5 If a certain contour line be chosen for piston K (Figure 1) resulting in producing for any two diametrically opposed piston positions (I or II respectively in Figure 1) an approximately constant sum of pump output (Q^I+Q^{II}=constant), the same law applies equally to the intake and delivery of piston k.

10 A double piston (Figure 4) consisting of a combination of two pistons 2^a, 2^b working in parallel arrangement with respect to their pumping action with eccentricities set at 180° rotating on a common shaft 6 will ensure a perfectly uniform pump output with a 15 double piston 3^a, 3^b rotating in the opposite direction on shaft 11 having analogous eccentricities also set at 180°.

20 A rotary pump having a single pair of pistons (Figures 2 and 3), however, will, in conjunction with its counter-piston of equal dimensions, ensure approximately constant pump output without the shape of the piston strictly complying with the equation 25 Q^I+Q^{II}=constant for two diametrically opposed positions. This result will be apparent from the following consideration:—

30 Piston 3 will act for piston 2 as the separating medium between suction side and delivery side, and vice versa. At equal radius the output of each piston is proportional to the radial distance of the point of contact with the counter-piston from the circumference of the casing.

35 Since maximum convergence between both pistons 2, 3 occurs in the course of a complete revolution within a zone adjacent to and definitely fixed by the plane enclosing the two axes of rotation of both pistons, the point of maximum convergence between the two piston 40 contours will be moving up and down closely adjacent to the centre-line c c' during one revolution, and the sum of the two distances of the point of maximum convergence from the circumferences of both casings will practically be constant and equivalent to the amount s (Figure 3).

45 In the construction of the rotary piston machine, in accordance with the principle of this invention, the shape of the pistons is dependent upon the service requirements to be met. The relation of the angles of the concentric piston sections of the intermediate curved sections of the piston profiles is chosen in such a manner that the degree of inequality of delivery never produces a condition in service which would cause a break in the flow of the liquid handled.

I claim:—

50 1. A rotary pump of the type having a pair of pistons which co-operate in the manner of a single or double tooth gearing, characterized by each of said pistons having a cam-shaped profile comprising a pair of concentric diametrically opposed, circular sections connected by intermediary sections,

the intermediary sections merging gradually with the circular sections and the entire profile of each piston being free from concaved or recessed portions.

2. A rotary pump of the type having a 70 pair of pistons which co-operate in the manner of a single or double tooth gearing, characterized by each of said pistons having a cam-shaped profile comprising a pair of concentric, diametrically opposed, circular sections connected by intermediary sections, the intermediary sections merging gradually with the circular sections and the entire profile of each piston being free from concaved or recessed portions, and means for rotating 75 said pistons at equal angular velocities, and the dimensions of the circular and curved sections of the profile of each piston, and the radii thereof with respect to their respective axes of rotation, being such that during each 80 rotation of each piston, maximum convergence, without actual contact of the piston profiles, occurs, whereby an intermediary film of liquid exists between the two pistons at their point of convergence and seals the 85 suction from the delivery side of the pump.

3. A rotary pump of the type having a 90 pair of pistons which co-operate in the manner of a single or double tooth gearing, characterized by each of said pistons having a cam-shaped profile comprising a pair of concentric, diametrically opposed, circular sections connected by intermediary sections, the intermediary sections merging gradually with the circular sections and the entire profile of each piston being free from concaved or recessed portions, one of the circular sections of each piston being of larger radius than its opposed circular section and the included angle of said larger circular section 95 being sufficiently large to cause said section, when each piston is in zero position with its larger section adjacent to its suction and delivery ports, to extend from the suction to the delivery port and thereby shut off communication between such ports. 100

4. In a rotary pump of the type wherein a pair of cam-shaped pistons are rotatable in a pump casing and operate in the manner of single or double tooth gearing, each piston having a profile consisting of a pair of concentric circular sections of different radii, and intermediate sections connecting and merging gradually with said circular sections in such a manner that the entire profile 115 of each piston is free from concaved or recessed portions, the radius R of one piston at every point of its profile being predetermined by the radius of the other piston r, at such point substantially in accordance 120 with the formula R+r=a constant, and so that an accurately predetermined amount of play is provided between the pistons at their point of convergence sufficient to prevent jamming of the pistons in their rota- 125 130

tion and to insure the presence of an intermediary film of sealing liquid between said pistons and at their points of convergence.

5. A rotary pump of the type having a pair of pistons which co-operate in the manner of a single or double tooth gearing, characterized by each of said pistons having a cam-shaped profile comprising a pair of concentric diametrically opposed, circular sections connected by intermediary sections, the intermediary sections merging gradually with the circular sections and the entire profile of each piston being free from abrupt, concaved or recessed portions.

10 15 In testimony whereof I affix my signature.
